UNITED STATES PATENT OFFICE.

JAMES S. HOPKINS, OF SOUTH FRAMINGHAM, MASSACHUSETTS.

OVERSHOE.

SPECIFICATION forming part of Letters Patent No. 317,360, dated May 5, 1885.

Application filed August 27, 1884. (No model.)

To all whom it may concern:

Be it known that I, JAMES S. HOPKINS, a citizen of the United States, residing at South Framingham, in the county of Middlesex and State of Massachusetts, have invented certain new and useful Improvements in Rubber Overshoes; and I do hereby declare that the same are fully described in the following specification and illustrated in the accompanying drawings.

This invention is designed to provide for lumbermen and others who work much in the snow an overshoe that will exclude snow and water much better than those in ordinary use.

15 My invention consists in a rubber overshoe provided with a flexible tongue secured to the shoe at one end, and extending upwardly without folds beneath the fastening devices.

20 My invention also contemplates cutting the lining or textile interior of such shoe in a single piece, to avoid seams, and also that the supports for its strap and buckle or other fastening devices are integral with the body of the shoe.

25 The drawings illustrate these peculiar features of my invention, Figure 1 showing the shoe complete. Fig. 2 is a longitudinal section of the shoe, and Fig. 3 a reduced duplicate of the pattern for cutting the lining or 30 body of the shoe in one piece.

In the manufacture of my improved shoe, as shown in the drawings, I place upon the sheet of fabric from which the lining is to be 35 cut the pattern A, Fig. 3, and with a sharp knife cut around the edges *a*, to form a complete lining in a single piece. I then cut out a nearly triangular portion, following the lines *b b* and *c*, and from the hole thus produced I cut the goods along the line *d* perpendicular to the base of the triangle cut away, and thus form, in one with the body, the supports *B*, to which the strap *C* and buckle *D* or other fastening devices are secured. The plastic sheet of rubber compound 40 to form the exterior surface of the shoe is preferably cut similarly, except as to the part *F*, which is not removed. The rubber may, however, be in two or more pieces, since the nature of the compound is such that the 45 pieces readily unite under the heat of vulcan-

izing when lapped or abutted against each other. The lining fabric will have the usual coating of rubber "frictioned" into it, so that the outer sheet will readily adhere. The tongue *E* is shown as cut of a nearly triangular shape, and is preferably of the same kind of material as the lining, and has the rubber-coated or water-proof surface on the outside. This coating may, if preferred, be somewhat heavier than the friction film of 55 rubber on the lining fabric. The tongue is secured at the point or small end only to the shoe—that is, its sides are free above the part *F* of the shoe, where the outer sheet of rubber overlaps it and holds it in place. In addition to this, the edges *b b* of the lining lap over the edges of the tongue at its lower end. The two are preferably cemented to each other along these edges before being lasted. I sometimes cut the tongue *E* in one with the 60 lining, instead of taking out the triangular piece, as stated; but I prefer to cement in the tongue and leave the fastening-supports *B* integral with the shoe itself. The parts of the lining lettered *G* on the pattern extend 65 around to the heel, and are there abutted smoothly together without a lap or ridge at the line *H*.

The various steps in the manufacture of the shoe I have not deemed it necessary to describe, since they are well known to manufacturers of rubber shoes.

I disclaim the well-known overshoe called the "Snow-Excluder," which has between the vamp and the quarters folded pieces of fabric 85 secured along each edge to said parts, but not constituting a free tongue; also the common Arctic overshoe having the vamp itself extended up over the instep in a single piece, or in two or more pieces stitched together. 90 I am also aware that many styles of leather shoes are furnished with leather tongues stitched at one end to the vamp. My purpose is to furnish rubber overshoes with equally useful water-proof tongues, and to provide 95 such shoes with linings seamless at front and sides, and with only a vertical abutted joint where the quarters meet at the heel.

I claim as my invention—

1. An overshoe having an external coating 100

of rubber, and within it a lining cut in a single piece, said shoe being provided with an elongated water-proof tongue secured at one end within the shoe, substantially as set forth.

5 2. An overshoe having an external coating of rubber and an internal lining of fibrous material, and provided with a tongue formed of material similar to the lining, with a film

of rubber on its upper surface, substantially as set forth.

In testimony whereof I hereto affix my signature in presence of two witnesses.

JAMES S. HOPKINS.
